CLEAT CLEANER

Dwaine G. Gentry, Manson, Iowa
Filed May 5, 1964, Ser. No. 79,828

Term of patent 14 years
(Cl. D9—6)

Fig. 1

Fig. 2

Fig. 3

Fig. 4

FIG. 1 is a plan view of a cleat cleaner, showing my new design;

FIG. 2 is a side elevational view thereof;

FIG. 3 is an end elevational view thereof, the cleat cleaner being viewed from the bottom of FIG. 1 within a horizontal plane; and

FIG. 4 is an elevational view of the oposite end thereof, as viewed from the top of the cleat cleaner of FIG. 1 in a horizontal plane.

The rear not shown is substantially flat and plain.

I claim:

The ornamental design for a cleat cleaner, substantially as shown and described.
